UNITED STATES PATENT OFFICE.

ROBERT H. McELROY, OF WILMETTE, ILLINOIS.

REFRIGERATOR CAR.

Application filed August 20, 1920. Serial No. 404,814.

To all whom it may concern:

Be it known that I, ROBERT H. McELROY, a citizen of the United States, residing at Wilmette, Illinois, in the county of Cook 5 and State of Illinois, have invented a new and useful Improvement in Refrigerator Cars, of which the following is a specification.

This invention relates to improvements 10 in refrigerator cars, and has for its principal object the provision of means whereby the quantity of ice in the car can be determined at all times without opening the ice compartment. In most cases the ice 15 compartments in refrigerator cars are filled from the top, so that when it is desired to know the amount of ice remaining in a compartment, it is necessary to climb to the roof of the car, remove the trap-door, and 20 make an inspection of the inside of the ice compartment. This requires time, labor and expense, and permits the entry of warm air into the ice compartment from the outside. With the use of my invention, the 25 amount of ice in an ice compartment may readily and quickly be determined from the outside of the car without opening the ice compartments.

When refrigerator cars arrive at an icing 30 terminal it is the practice in railroad operation to set the cars out for inspection and icing. This necessitates the opening of the hatch and many times inspection indicates the car as being properly iced when, as a 35 matter of fact, there may be only a crust of salt that has formed and no ice in the compartment. Such a car is allowed to go forward as being properly iced and may result in a damage claim amounting to thousands 40 of dollars, depending upon the character of the perishable goods being transported.

If, however, an inspection does show the car requires icing, it is switched to an icing 45 plant at a material cost, as switching expenses today are materially higher than they have ever been before. With the use of the device involved in this construction, it would be wholly unnecessary to switch 50 the car if the dial on the outside of the car indicated there was sufficient ice to run the car safely to the next icing station.

Furthermore, it would be unnecessary to 55 open the hatch for examination, as the dial would more clearly show the condition of the icing compartment without the necessity

of opening the hatch and letting in atmospheric temperature, which in many cases would result in warming the entire compartment and losing just that much ice, 60 which today is very much more expensive than has been the case for many years past.

The record of the condition of the car, as based on the reading of the dial by the use of this device, would indicate clearly 65 the amount of ice in pounds at the icing station and, with such a record, the carriers would be able to substantiate, in the event of a claim, the fact that the car was fully iced through to destination. 70

A saving in the number of refrigerator cars employed would be accomplished, more than any saving in mileage, by reason of the elimination of delays at icing terminals and in this way would require less refriger- 75 ator equipment than under the present plan.

In general, my invention comprises a scale pan or load platform arranged in the bottom of the ice compartment upon which the ice rests. The load platform is connected with a weight indicator visible from the outside of the car so that the weight of ice in the compartment may be readily noted from the outside by looking at the indicator. I also provide means for rendering the scale mechanism inoperative 80 while the car is in transit, and while ice is being loaded into the compartment, so that the scale mechanism will not be injured by jarring. It is obvious, however, that, without detracting from the spirit of this invention, such means for rendering the scale mechanism inoperative may be dispensed with if desired; because it would be possible to make the mechanism strong and heavy 85 enough to withstand the jolts of travel, and the jars of ice falling into the compartment. 90 95

In that form of device embodying the features of my invention, shown in the accompanying drawings, Figure 1 is a view in end elevation of the body of a refrigerator car, with a portion of the end wall removed showing the interior of the ice compartment. Fig. 2 is a longitudinal sectional view taken on the line 2 of Figure 1. Fig. 3 is a horizontal sectional view taken on the line 3 of Fig. 2. Fig. 4 is a vertical sectional view taken on the line 4 of Fig. 3. 100 105

As shown in said drawings, 6 indicates in 110 general the body of a refrigerator car in which the ice compartment in one end is

indicated by 7, and the ice therein by 8. Access to the ice compartment 7, for filling, is had through the trap-doors 9 on the roof of the car. Such parts may be of any ordinary construction and form no part of the present invention. Likewise, ducts, or openings, for permitting circulation of air back and forth from the ice compartment 7 to the interior of the car 10, of any suitable form or construction may be provided; and since they form no part of the present invention, are not described or shown in particular in the drawings.

Arranged slightly above the stationary bottom 12 of the ice compartment is a scale pan or load platform 13 supported by four short arms 14 at the corners suspended by four chains 15 extending upwardly and over the sprockets 16 mounted on the two parallel shafts 17 suitably supported near the top of the car. The chains 15 extend over the sprockets 16 and then downwardly, with their ends attached to the upper ends of spiral springs 18 which in turn have their lower ends attached to the eyes 19 suitably fastened to a part of the car body. Each of the parallel shafts 17 carries rigidly mounted thereon two of the sprockets 16, and in addition near each end an additional sprocket 21. Each pair of sprockets 21 at the adjacent ends of the shafts 17 are connected by an endless chain 22, so that rotation of one shaft 17 will necessarily cause rotation of the other. The function of the connection between the two shafts 17 by the chains 22 is to prevent tipping of the load platform 13. With such connection it is impossible for one side to move upwardly or downwardly more rapidly than the other. The chains 15, springs 18, and shafts 17 with the sprockets carried thereby are all arranged between the double walls at the sides of the ice compartment; such double walls at the end of the car being indicated by 31 and 31^a, and the double wall between the ice compartment and the interior of the car 10 being indicated by 32 and 32^a. The arms 14 extend through the slots 35 and 36 provided in the walls 31 and 32 respectively. One of the chains 15 at the end of the car is somewhat shorter than the other three, and has interposed between its end and the spring 18 a short bar 40 with an indicator 41 projecting outwardly through a slot 42 in the outer wall 31^a of the car. At the side of the slot 42 a suitable index 45 is arranged in order that travel of the indicator 41 may be noted. The tension of the springs 18 is such that when the ice compartment 7 is substantially full, the springs will be extended and the indicator 41 will be nearly to the top of the index, and when it is empty, such indicator will be nearly to the bottom with the springs compressed. If desired, markings may be put on the index

45 in order to record the weight of the ice on the load platform for the different positions of the indicator 41. The load platform 13 is perforated as indicated by 50 in order to permit the drainage of water from 70 the melting ice.

I have also shown means for rendering the weighing mechanism inoperative in order to prevent damage from jars or jolts during transit or during the filling operation. It is obvious, however, that such means may be dispensed with, or not used, without departing from the spirit of my invention; since it would be possible to make the parts heavy enough to withstand such jars and jolts. Such means, as I have shown them, comprise a brake-drum 55 mounted on the shafts 17 which is supported near the end of the car. Such brake-drum 55 is surrounded by a brake-band 56 adapted to be held tightly around the drum by the compression spring 57 operating between the wall 31^a and the stop 58 arranged on the bar 59 which in turn has its end attached to a lever 60 mounted on a short rotatable shaft 61 carrying on one end the cross piece 62 to the ends of which are attached the ends of the brake-band 56. The bar 59 extends outwardly through the wall 31^a and terminates in the handle 65 permitting it to be pulled out to compress the spring 57, rock the shaft 61 and cross piece 62, thus loosening the brake-band 56 and permitting rotation of the drum 55 and shaft 17. As shown, the parts are so arranged that normally the spring 57 will prevent rotation of the shaft 17, and consequently prevent any movement upwardly or downwardly of the load platform 13, thus preventing bouncing up and down of the load platform and movement of the springs from jars and jolts in transit or during the filling process. When it is desired however, to permit movement of the load platform in order that the indicator 41 might show the weight of the ice thereon, all that is necessary is to pull the handle 65 outwardly, thus releasing the brake-drum 55 and permitting rotation of the shaft 17, whereupon the load platform 13 will take such position as may be determined by the weight of ice thereon with the consequent indication by the indicator 41. If desired, the means for holding the platform may be dispensed with by removing the brake-drum 55 or such means 110 may be rendered inoperative by pulling out the handle 65 and holding the same in such position by inserting a suitable wedge between the shoulder 80 on the rod 59 and the wall 31^a.

125 While I have shown and described certain embodiments of my invention, it is to be understood that it is capable of many modifications. Changes therefore in the construction and arrangement may be made 130

without departing from the spirit and scope of the invention as disclosed in the appended claims, in which it is my intention to claim all novelty inherent in my invention 5 as broadly as possible in view of the prior art.

Although I have shown the weight indicator as being located at the end of the car, it is obvious that, without detracting from 10 the spirit of this invention, it may be placed at the side of the car. Perhaps, in ordinary use, the side of the car would be a better location for the weight indicator than the end, because so located the weight indica- 15 tors on separate cars in a train could be more easily observed by any one walking along the side of the train.

What I claim as new and desire to secure by Letters Patent is:

20 1. The combination with a refrigerator car having an ice compartment, of an ice receiving platform suspended in the ice compartment, and a weight indicator on the outside of the body of the car and connected 25 to the platform suspension means, whereby variations in the weight of the load of ice carried by said platform may be seen without opening said ice compartment.

2. The combination with a refrigerator 30 car having an ice compartment, of an ice receiving platform suspended in the ice compartment and a weight indicator on the outside of the body of the car and connected

to the platform, suspension means to indicate the upward and downward movements 35 of said platform due to variations in the load of ice carried thereby, whereby variation in such load may be seen without opening said ice compartment.

3. The combination with a refrigerator 40 car having an ice compartment, of an ice supporting platform therein, means connected with said platform to cause the same to move vertically with variations in the weight of the ice thereon, and a weight in- 45 dicator on the outside of the body of the car and connected with said platform for indicating the vertical movements thereof, whereby variations in the weight of the ice carried by said platform may be seen with- 50 out opening said ice compartment.

4. The combination with a refrigerator car having an ice compartment, of weighing mechanism comprising an ice receiving platform suspended in the ice compartment, 55 and a weight indicator on the outside of the body of the car and connected with said platform, whereby variations in the weight of the load of the ice carried by said platform may be seen without opening said ice 60 compartment, and means for rendering said weighing mechanism inoperative.

In testimony whereof, I have hereunto set my hand and seal this 16th day of August A. D. 1920.

ROBERT H. McELROY. [L. s.]
